VALVE ACTUATING DEVICE

Henry U. Garrett and Clifford M. Peters, Longview, Tex., assignors, by mesne assignments, to U.S. Industries, Inc., a corporation of Delaware.

Application May 16, 1955, Serial No. 508,562

20 Claims. (Cl. 166—214)

This invention relates to a well apparatus wherein a valve means or other member is shifted from one position to the other by manipulation of a mechanism in a well. In another of its aspects, it relates to wire line tools particularly adapted to shift such valve means or member and to mechanisms for determining or indicating when the shifting has been properly accomplished.

In co-pending application Serial No. 330,294, filed January 8, 1953, now Patent No. 2,804,830; there is shown a well apparatus wherein a valve means or sleeve-like member is shifted from one position to another, or between three positions, to control flow through one or more ports in a well conduit. In the same application, a wire line tool for effecting such shifting is described and claimed and it is a general object of this invention to provide improvements upon a tool of that same general nature.

In co-pending applications Serial No. 374,296, filed August 14, 1953, now Patent No. 2,790,501; Serial No. 414,924, filed March 9, 1954, now Patent No. 2,790,395; Serial No. 449,632, filed August 13, 1954, now Patent No. 2,818,925; Serial No. 435,984, filed June 11, 1954, now Patent No. 2,808,781; and Serial No. 484,164, filed January 26, 1955, there are described various other arrangements of valve means or other members for effecting various well operations including not only the control of flow through a port in a well conduit but also the setting of a packer and the like. In each of these cases, the valve means or other member is shiftable and hence it is desirable to provide a tool for accomplishing such shifting.

In the specific embodiments of the apparatus described in the above applications, a sleeve is shiftable axially of the well conduit by a wire line tool and, as a matter of practice, wire line jars are frequently used in conjunction with the shifting tool in order to apply a jarring action to the sleeve. When the sleeve is to be moved downwardly, the shifting tool can be supported by the sleeve while the wire line is manipulated to effect operation of the jars. However, when the shifting tool is to move the sleeve upwardly, any slackening off of the wire line tool to operate the jars normally results in the shifting tool dropping away from the sleeve so that a proper jarring action cannot be accomplished but instead, the shifting tool is itself reciprocated and rammed into the sleeve to deliver an impact blow thereto.

In the shifting tools specifically described in the above applications, there is provided at least one dog which engages the sleeve to move it upwardly after which a frangible connection between the dog and the tool housing is severed to permit the dog to retract to free the tool to be removed from the hole. The frangible connection is of such nature that a considerably greater upward pull on the wire line is required to sever the connection than to cause the sleeve to shift upwardly. As a result, there is a fairly positive assurance that the sleeve has been properly shifted to its upper position. However, in moving the sleeve downwardly, dogs are employed to engage the sleeve and then the entire tool

2

is jarred or pushed downwardly. With such an arrangement, it is difficult to be positive that the sleeve has been shifted downwardly as far as desired since there is no releasable connection or the like which given an operator a positive indication of proper sleeve shifting as is the case when the sleeve is moved upwardly. As a result, it has sometimes been the practice to jar the tool downwardly with a great deal more vigor and for a longer period of time than is actually required to shift the sleeve. It would be highly desirable to possess an indicating tool to positively determine when the sleeve has been properly shifted and before the wire line tool has been removed from the hole.

As mentioned above, the shifting tools specifically shown in the above applications have a dog which is frangibly mounted on the tool to push the sleeve upwardly after which the mounting is severed to retract the dog and release a downwardly facing dog which can engage the sleeve to move it downwardly. With such a tool and when a plurality of sleeves are to be manipulated in a well, all upward shifting of the sleeves must be serially from top to bottom and all downward shifting from bottom to top. It would be highly desirable to possess such a shifting tool having an improved mechanism permitting alternate retraction and extension of the dogs any number of times while the tool remained in the well so that sleeves could be shifted in any direction in any desired sequence.

It is an object of this invention to provide a tool for engagement with an abutment in a well wherein a first dog is retracted and a second dog permitted to move to extended position responsive to relative movement between two parts of the tool, such movement being effected by holding one such part against movement by the first dog while the second part is moved by manipulation of a wire line or other means whereby the action of the tool is made positive and not susceptible of failure.

Another object is to provide a tool of such type in which a plurality of dogs can be employed to engage a valve means or other member to hold one tool part against movement while the other tool part is being moved by a wire line, there being provided a releasable means restraining relative movement between such parts until a predetermined moving force has been applied to the other tool part, whereby at least such force is always applied to the valve means or other member even though the dogs are unevenly engaging the valve means or member with consequent unequal distribution of such force among the dogs.

Another object is to provide a well apparatus wherein a member to be shifted in a well conduit is engaged for such purpose by a wire line tool, the tool having oppositely facing first and second dogs alternately operable to shift the member in opposite directions and a mechanism for moving one dog to retracted position while releasing the second dog and then, without removing the tool from the well, retracting the second dog while releasing the first dog so that the shiftable member can be shifted upwardly and downwardly any desired number of times or a plurality of such members can be shifted as desired in any sequence, all without removing the tool from the well.

Another object is to provide a wire line tool having oppositely facing dogs respectively engageable with oppositely facing abutments in a well to limit movement of the tool past such abutments and arranged so that the respective dogs permit free movement of the tool away from the respective abutments engageable thereby, there also being provided means for alternately retracting the dogs any number of times while the tool is in the well so that the tool can selectively engage a plurality of abutments in a well in any desired sequence during upward

or downward movement of the tool in the well or during any desired sequence of both such movements.

Another object is to provide a wire line tool having upwardly facing dogs engageable with an abutment in a well to limit upward movement of the tool but permitting free downward movement thereof, the tool also being provided with additional means engageable to support the tool independently of the wire line whereby jars in the wire line can be properly actuated to give true jarring action.

Another object is to provide a wire line tool which can be supported in a well against downward movement therein independently of the wire line and yet is free to move upwardly so that jars in the wire line can be properly actuated to move the tool upwardly without the tool dropping each time the wire line is slackened to begin a jarring stroke.

Another object is to provide a wire line tool for moving a valve means or sleeve-like member from one position to another and for then testing the position of such means or member to assure that it has been moved to the desired position, all without removing the tool from the well and by wire line manipulation.

Another object is to provide a locator operable by a wire line to determine the position, relative to a well conduit, of a shiftable valve means or sleeve-like member.

Other objects, advantages and features of this invention will become apparent to one skilled in the art upon a consideration of the written specification, the appended claims and the attached drawings wherein:

Figs. 1A and 1B illustrate a preferred embodiment of a wire line tool for shifting a valve means or sleeve-like member in accordance with this invention, it being understood that Figs. 1A is a continuation of Fig. 1B with the latter representing a lower portion of the tool and also that the portion of Fig. 1A so designated has been rotated 90° from its actual position to better illustrate the construction;

Figs. 2A and 2B are views similar to those of Figs. 1A and 1B except that the parts of the tool are shown in another operating position;

Fig. 3 is a section taken on the line 3-3 of Fig. 1A;

Figs. 4, 5 and 6 are views showing the tool of the preceding figures in operation in shifting a sleeve valve in a well conduit disposed in the well;

Fig. 7 illustrates another embodiment of a tool for shifting a sleeve-like member or valve means, certain portions of the tool which can be constructed like the corresponding portions of Figs. 1A and 1B being omitted from the showing;

Fig. 8 illustrates a wire line tool for suspending another tool in the well to permit proper upward jarring action of wire line jars;

Fig. 9 illustrates the tool of Fig. 8 in operation in a well in combination with a shifting tool for moving a sleeve-like member or valve means upwardly;

Fig. 10 is an alternative embodiment of the tool of Fig. 8;

Fig. 11 is an illustration showing a mode of use of the tool of Fig. 10; and

Figs. 12 and 13 illustrate a locator tool in use with a shifting tool to determine the location of a valve means or sleeve-like member in a well.

Like characters of reference are used throughout the several views to designate like parts.

Referring to Figs. 1A and 1B, the shifting tool illustrated generally comprises an upwardly facing pair of dogs 15 and 15a and a downwardly facing pair 16 and 16a. The dogs are respectively pivotally mounted on pins 17 and 17a and on pins 18 and 18a so that the dogs can move their engaging ends 19-19a and 20-20a laterally of the tool between extended and retracted positions. Each of the dogs is biased to extended position by suitable resilient means such as springs 21 and 22. Each of the dogs has a tapered portion 23 which, with the dogs

in extended position, can encounter any projections, abutments or shoulders in the well conduit to move the dogs toward retracted position to permit the tool to continue its movement through the conduit. With this construction, it will be apparent that with dogs 15 and 15a in extended position as shown, the tool can be lowered downwardly through the well and the dogs will be moved inwardly to permit the tool to pass obstructions in the tubing or can even be held by the tubing in partially or completely retracted position ready to spring out into any enlarged portion of the tubing. Upon upward movement of the tool, dogs 15 and 15a can then engage suitably placed abutments or shoulders in the well to limit upward movement of the tool. Similarly, dogs 16 and 16a permit the tool to be raised in the well conduit without engaging any abutments or shoulders to stop raising of the tool but upon downward movement of the tool, the dogs are engageable with abutments and shoulders to so limit the movement of the tool.

In accordance with this invention, means are provided for holding the downwardly facing dogs 16 and 16a in retracted position while permitting the upwardly facing dogs 15 and 15a to move to extended position. Such means is operable by manipulation of the wire line or other supporting means for the tool to retract the upwardly facing dogs and release the downwardly facing ones for movement to extended position. Such means is provided by making body part 24, which carries the dogs, movable axially relative to body part 25. Then body part 25 is provided with an enlargement 26 engageable with fingers 27 of the downwardly facing dogs to hold them in retracted position. Upon upward axial movement of body part 25, enlargement 26 is likewise moved upwardly to release the downwardly facing dogs for movement to extended position as shown in Fig. 2B. It will be noted that enlargement 26 has a downwardly facing shoulder 28 engageable with opposing shoulder 29 on the downwardly facing dogs so that a jarring force can be transmitted by body part 25 directly through the dogs to an abutment in the tubing against which ends 20-20a of the dogs engage. In this manner, the jarring force need not be taken across pivot pins 18 or 18a.

To retract the upwardly facing dogs upon upward movement of body part 25, a retracting ring 30 is disposed around a reduced diameter portion 31 of body part 25 and is urged upwardly by a spring 32 to normally abut a stop 33. Fingers 15b of dogs 15 and 15a have a tapered part 15c engageable by ring 30 to move the dogs to retracted position as shown in Fig. 2A. With this construction, upward movement of body part 25 immediately releases the lower dogs 16 and 16a for movement to extended position and also moves ring 30 into position to retract the upwardly facing dogs. In case the upwardly facing dogs are engaging an abutment in the well with such force that it would be difficult to move them to retracted position, upward movement of body part 25 merely compresses springs 32 so that upon partial or total disengagement of the upwardly facing dogs from the abutment, ring 30 is pressed into place as shown in Fig. 2A to retract the dogs.

Releasable detent means are provided between body parts 24 and 25 preventing axial movement therebetween until a predetermined force has been applied to cause such movement. As shown in Figs. 1A and 2A, such means includes a frangible connection in the form of a shear pin 34 extending through registering openings in body parts 24 and 25. The upper end of body part 25 has a portion 35 adapted to be connected with a wire line so that with dogs 15 and 15a engaging a downwardly facing abutment in the well, an upward pull on the wire line exerts force via the shear pin and through these dogs onto the well abutment. As the force is increased, it will eventually become great enough to shear pin 34 and permit the body part 25 to move upwardly as shown in Fig. 2A. The body part 25 is maintained in its upper

position by spring 36 extending between the body parts and upward movement is limited by a nut 37 engaging a lower portion 38 of body part 24.

To facilitate removal and replacement of the shear pin, retaining collar 39 has a sliding fit on the upper end of body part 24 so that it can be lifted up against spring 36 and shear pin 34 slid into place. The sleeve can then be lowered and will retain the pin. In Fig. 2A, pin 34 is shown sheared and, if desired, knockout holes 40 can be disposed in the body portion 24 to permit the part of the pin in body portion 25 to be easily removed and a knockout hole 41 can be disposed in body portion 25 to permit the two pin portions in body portion 24 to also be knocked out.

In order to prevent relative rotation between the two body parts, a lock pin 42 can be disposed in body part 24 with a portion thereof sliding in a slot 43 in body part 25.

Referring now to Figs. 4, 5, and 6, there is shown a well conduit 50 having ports 51 therein controlled by a shiftable valve means or a sleeve 52. The sleeve has an imperforate portion 53 so that when it is in its low-remost position, this portion blocks flow through ports 51. The sleeve also has ports 54 adapted, when the sleeve is raised to its upper position, to register with ports 51 to permit fluid flow between the interior and exterior of the well conduit. The sleeve is free for movement between two positions as shown in Figs. 4 and 5.

The tool of Figs. 1A-1B is shown in elevation in Figs. 4, 5 and 6 as suspended from a wire line 55 via a set of wire line jars 56. With the parts of the tool positioned as shown in Figs. 1A and 1B, the shifting tool can be lowered through the well conduit until it reaches a point below sleeve 52. Thereupon, upward movement of the tool permits dogs 15 and 15a to move out and engage the lower end 57 of sleeve 52. Continued upward force applied by wire line 55 will cause the sleeve to move upwardly, aided by jarring action if desired. After the sleeve has been moved upwardly to its Fig. 5 position, an added upward force on the wire line will cause shear pin 34 to shear so that the parts of the tool assume the Figs. 2A-2B position. This retracts the upwardly facing dogs and permits the downwardly facing dogs 16-16a to move to extended position where they are free to engage the upper end 58 of sleeve 52 to limit movement of the shifting tool downwardly. Then by jarring downwardly with the wire line, the sleeve can be moved back to its Fig. 4 position if desired. Of course, after this operation has been completed, the shifting tool can be moved upwardly through the well conduit to engage the upper ends of any succeeding sleeves thereabove.

While only one sleeve has been shown in the conduit of Figs. 4-6, a plurality of these sleeves can be spaced at various depths along a well conduit. Then the shifting tool can be lowered to move one or more of these sleeves upwardly by working from the topmost sleeve toward the bottom. After the bottom sleeve has been shifted, the upwardly facing dogs can be retracted and the tool then employed for downward shifting of the sleeves serially from bottom to top.

It will also be seen that the tool of this invention can employ a plurality of dogs although only two have been shown in the drawings. By the use of a single shear pin to govern retraction and extension of the dogs, there will always be required at least a predetermined force to cause such retraction and extension even though the upwardly facing dogs may unevenly engage the sleeve. Thus, for example, when using a pair of upwardly facing dogs, if only one of them should for some reason engage the sleeve, it still requires the same upward force on the wire line to shear pin 34 as it would if both dogs were in equal engagement with the sleeve. As a result, one can be assured that at least such predetermined force is applied to the sleeve to shift it up-

wardly and by making shear pin 34 of a size that the force to shear it is always greater than that required to shift a sleeve, the sleeve will always positively be shifted upwardly before the upper dogs are retracted.

With the tool as just specifically described, it will be seen that once the downwardly facing dogs are moved to extended position, it is not thereafter possible to move a sleeve upwardly without first removing the tool from the well to replace the shear pin. With the arrangement of Fig. 7, the upwardly and downwardly facing dogs can be alternately retracted and permitted to move to extended position as many times as may be desired without removing the tool from the well. In this arrangement, the shear pin of Figs. 1A and 1B is replaced by a latch ring 60 carried within a sleeve 61 forming a depending extension from housing part 25. Ring 60 has inwardly extending tapered portions 62 and 63 adapted to engage a groove 64 in a split spring ring 65. With this arrangement, the lower dogs 16-16a will be held in retracted position until enough upward force is applied on body part 25 by the wire line to cause the split ring 65 to be contracted inwardly to release portion 62 and ring 60 for upward movement with body part 25. As soon as the body part 25 has moved upwardly sufficient to release dogs 16-16a and retract dogs 15-15a, portion 63 will enter groove 64 to limit further upward movement. By applying a downward force on body part 25 while holding body part 24, the above action is reversed. In this manner, body part 25 can be shifted axially in either direction with respect to body part 24 to alternately retract the upwardly and downwardly facing dogs as many times as may be desired. In connection with this, it will be noted that the upper ends of dogs 16 and 16a have a tapered portion 35a engageable with a ring 30a which moves the dogs into and holds them in retracted position. Both rings 30 and 30a are urged toward shoulder stops 66 and 67 respectively by spring 32 so that the spring can be compressed by movement of body part 25 to subsequently retract one pair of dogs when the latter are too tightly engaged during movement of body part 25 to then permit their retraction.

In order to assist sleeve 60 and ring 64 in holding the body parts in one position or the other until a desired force has been applied to cause them to shift, spring 32 is disposed between two releasable detent members comprising rings 68 and 69 slidable on body part 25 and each having resilient latch fingers 70 and 71 respectively engageable with shoulders 72 and 73 formed on a center piece 74 of body part 24. The shoulders and latch fingers are so spaced that the latch fingers will respectively engage shoulders 72 and 73 when the body part 25 is in its downmost and uppermost positions. With this construction, the accidental application of excessive force tending to contract ring 64 and permit body part 25 to prematurely move upwardly is opposed by force exerted by spring 32 which in effect is added to the upward force required to contract ring 65. If desired, the spacing between portions 62 and 63 can be made slightly greater than the spacing between the adjacent ends of latch fingers 70 and 71 so that the end of one latch finger engages the end of the other to dislodge it from its engagement with portions 72 or 73 before body part 25 has undergone its complete movement whereby the engagement between the latch fingers and portions 72 and 73 can be made very firm and spring 32 of considerable strength. This helps prevent premature movement of body part 25.

The operation of the tool of Fig. 7 is substantially like that described with reference to Figs. 4, 5 and 6 except that the dogs can be alternately retracted and extended without removing the tool from the well as described above.

Referring now to Figs. 8 and 9, there is shown a tool which can be formed as a part of the shifting tool of Figs.

1A-7 to support the shifting tool against downward movement in the well conduit whereby a wire line can be slackened off to actuate jars without the shifting tool also dropping down the conduit. The holding tool illustrated in Fig. 9 is particularly designed for operation in conjunction with valve means or sleeves having a passage therethrough which is smaller than the tubing. Thus as shown in Fig. 9, an outer sleeve 80 is mounted in a mandrel 81 to control a port 82 in the mandrel. An inner sleeve 83 is provided and is connected to the outer sleeve by a web 84 through which an innerconnecting passageway 85 extends. The lower part of inner sleeve 83 can be formed with receiving means to latch a gas lift valve or the like in place as shown and described in co-pending application Serial No. 414,924, filed March 9, 1954. The receiving means illustrated is provided with shoulders 86 which are engageable by dogs 15 and 15a of the shifting tools so that the sleeve can be shifted upwardly to close off ports 82.

Referring now to Fig. 8, there is provided a body 87 having its ends formed so as to be connectible with wire line jars and a shifting tool. Disposed in lateral bore 88 in body 87 is a pair of balls 89. The balls partially extend through an opening 90 in a retainer sleeve 91 and are pressed outwardly into this opening by a spring 92 acting against a cam ring 93. The distance between the radially outermost portions of balls 89 when they are in the position of Fig. 8 is made somewhat greater than inside diameter of the sleeve to be shifted so that the balls will frictionally engage the sleeve and preferably rest upon an upper end thereof. Spring 92 is made of such strength that the balls are pressed outwardly with sufficient force that the frictional engagement of the balls supports the weight of the shifting tool against downward movement when the wire line is slackened off. On the other hand, force can be applied by the jars to retract the balls and push the support tool downwardly through the sleeve or by the wire line to pull the tool upwardly through the sleeve.

In order to accommodate various lengths of sleeves, an additional lateral bore 94 as well as additional ball openings 95 can be provided in the tool. Then by placing another ring 96 so as to be urged downwardly by spring 92 to urge any balls in bore 94 outwardly, it is possible to move balls 89 from bore 88 to bore 94 to cooperate with a shorter sleeve. It will be noted that a guide 97 is inserted interiorly of rings 93 and 96 and has a stop 98 to hold ring 96 against excessive movement when the balls are in the upper bore.

It will thus be seen that the tool of Fig. 8 can be connected to one of the shifting tools as shown in Fig. 9 and lowered through the well conduit by wire line apparatus including jars 56. When the shifting tool has been positioned with dogs 15 and 15a engaging shoulders 86, spring 92 of the support tool holds balls 89 outwardly in frictional engagement with inner sleeve 83. This permits the wire line to be slackened off so as to properly actuate the jars and yet the shifting tool is supported by the support tool so that dogs 15-15a do not drop away from shoulders 86. This type of arrangement avoids having to ram dogs 15 and 15a into shoulders 86 to achieve a jarring action.

Referring now to Figs. 10 and 11, there is shown another embodiment of a support tool in which the frictionally engaging elements of Fig. 8 are replaced by a pair of extensible and retractable dogs 100 and 100a. The dogs are urged by springs 101 to pivot about pivots 102 to move lower ends 103 outwardly for engagement with an upwardly facing abutment in the well. As shown in Fig. 11, such abutment is the upper end of a sleeve 103. The dogs are held in retracted position by an enlargement 104 on a body part 105 whose upper end is connected to the wire line jars as indicated in Fig. 11. The upper end of the tool of Fig. 10 is provided with a releasable detent such as the shear pin arrangement shown in Figs. 1A

and 2A so that the inner body part 105 is held in its down position until the shear pin is broken by an upward pull on the wire line. As soon as this happens, enlargement 104 moves upwardly with body part 105 and the dogs 5 move to extended position. In operation, outer body part 106 is connected to one of the shifting tools as shown in Fig. 11 and the same is lowered into the well conduit until dogs 15-15a of the shifting tool engage the lower ends of sleeve 103. An upward pull on the wire line causes the shear pin at the upper end of the holding tool to shear thereby permitting dogs 100 and 100a to move to extended position. In this connection, it should be noted that the shear pin for the holding tool is made to shear with less force than that required to shear the pin for retracting dogs 15 and 15a.

Dogs 100 and 100a are spaced from dogs 15 and 15a a distance such that when each are in extended position, the distance therebetween will be equal to or slightly greater than the length of sleeve 103 whereby the dogs of the supporting tool rest upon the upper end of the sleeve to hold the dogs 15 and 15a in close engagement with the lower end of the sleeve. Then by slackening off on the wire line and actuating jars 56, the sleeve can be moved upwardly. The jarring can be continued until the shear pin in the shifting tool shears and then the entire mechanism removed from the well.

As indicated above, downward movement of a valve means or sleeve-like member is a well conduit by a wire line manipulation frequently involves difficulty in determining when the valve means or sleeve-like member has been moved to its desired positions. In accordance with this invention, a locator tool is provided, particularly for use in combination with a shifting tool, to indicate or determine when the valve means or sleeve-like member 30 has been properly shifted. Thus, referring to Fig. 12, the locator tool 110 is shown suspended from a shifting tool 111 by means of a spacer bar 112. The locator tool here illustrated is constructed like the shifting tool (e.g. as shown in Figs. 1A-2B) except that the dogs 16c and 16d are made so that when they are extended, they will limit movement of the locator tool only when the sleeve has been shifted to its desired position and will otherwise permit the locator tool to move past the sleeve.

Thus, sleeve 113 in conduit 144 has ports 115 adapted to register with ports 116 when the sleeve is in an uppermost position. Upon downward movement of sleeve 113 until its lower end abuts a shoulder or stop 117 in the conduit, an imperforate portion of the sleeve is then situated opposite conduit ports 116 to prevent flow therethrough. The upper end of sleeve 113 when it is in its uppermost position abuts a shoulder 118 in the conduit and extends inwardly slightly therebeyond to provide a shoulder for engagement with the downwardly facing dogs of a shifting tool.

55 The well conduit has a portion 120 disposed to engage straight sided parts of the dogs between lower ends 121 and upper ends 122 thereof and prevent the dogs from moving out to engage their ends with the upper end of the sleeve. Then as the dogs move downwardly and as long as they contact conduit portion 120, they cannot move to extended position sufficiently that the sleeve will stop the tool. The sleeve has a portion 119 which also engages the straight sided parts of the dogs whenever the sleeve is in other than its lowermost position. In effect then, the dogs bridge across conduit and sleeve portions 120 and 119 when the sleeve has not been moved to its lower position. However, when the sleeve is moved to its lower position, portions 119 and 120 are moved apart to provide a recess therebetween into which dogs 16c-16d move as soon as they disengage from conduit portion 120. The resultant abutment of the dogs with the upper end of the sleeve stops the locator tool thereby indicating the sleeve has been properly shifted. It will thus be seen that sufficient shifting of the sleeve provides a dog receiving recess of sufficient length to receive the

dogs and stop the tool but insufficient shifting of the sleeve results in the recess being too short to receive the dogs so that they bridge thereacross and fail to stop the tool.

In explaining the operation of the assembly of Figs. 12 and 13, assume that sleeve 113 is in its uppermost position and is to be shifted downwardly. The locator tool, spacer bar and shifting tool are assembled on a wire line as shown in Fig. 12 and lowered into the well conduit with dogs 15 and 15a of each of the shifting tool and locator tool being free to move to extended position. As soon as the shifting tool reaches a position below the sleeve, it is pulled upwardly until its dogs 15 and 15a engage the lower end of the sleeve. An additional pull will then cause the shear pin in the shifting tool to shear (or the two-way detent to be released) whereby dogs 15-15a are retracted and the downwardly facing dogs 16-16a are permitted to move to extended position. The tool is then pulled upwardly in the well until dogs 15-15a of the locator tool engage the lower end of the sleeve and an additional pull exerted to retract dogs 15-15a of the locator tool and permit dogs 16c-16d to move to extended position. The tool is then lowered back down the well until dogs 16-16a of the shifting tool engage the upper end of the sleeve and then jars 56 can be actuated to shift the sleeve downwardly. As soon as the operator thinks that the sleeve has been properly shifted downwardly, he can pull up on the wire line a distance such that dogs 16c-16d will be above the sleeve. Then upon lowering the wire line, dogs 16c-16d will move outwardly into the recess between the sleeve and conduit portions 119 and 120 to engage the upper ends of the sleeve as shown in Fig. 13. The operator will then note a slackening on his wire line and can be assured that the sleeve 113 has been properly shifted.

Should the sleeve 113 not have been shifted sufficiently far downwardly, dogs 16c-16d will bridge between sleeve and conduit portions 119-120 and permit the locator tool to move downwardly again through the sleeve. This excessive downward movement will indicate to the operator that the sleeve has not been shifted downwardly to its proper position. He can then continue lowering the tool until the downwardly facing dogs of the shifting tool again engage the sleeve to repeat the operation.

The various shifting tools of this invention can be combined with the locator tools and holding tools to provide various combinations as will be apparent to one skilled in the art.

From the foregoing it will be seen that this invention is one well adapted to attain all of the ends and objects hereinabove set forth, together with other advantages which are obvious and which are inherent to the apparatus.

It will be understood that certain features and sub-combinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

We claim:

1. A wire line tool manipulatable in a well to selectively engage upwardly and downwardly facing abutments therein comprising, in combination, first and second body parts connected together for movement axially relative to each other with the first body part being connectible with a wire line, first and second oppositely facing dogs carried by the second body part for movement between extended and retracted positions and in extended position, said first dog being engageable with said downwardly facing abutment

to limit upward movement of the tool and said second dog being engageable with said upwardly facing abutment to limit downward movement of the tool, said dogs being urged toward extended position, means carried by the first body part to retract the first dog and to release the second dog for movement from retracted to extended position upon axial movement of the body parts relative to each other in one direction and to release the first dog for movement from retracted to extended position and to retract the second dog upon axial movement of the body parts relative to each other in an opposite direction, and means preventing relative axial movement between said parts from one position to the other, said movement preventing means being releasable to permit said relative axial movement upon one of said dogs engaging its respective abutment and a force of predetermined magnitude being applied to the first body part to move it axially relative to the second body part.

2. The tool of claim 1 wherein said dogs are pivoted to said second body part for movement of oppositely facing ends thereof between extended and retracted positions and means are provided resiliently biasing the dogs to extended position.

3. A wire line tool manipulatable in a well to selectively engage upwardly and downwardly facing abutments of a well apparatus in the well comprising, in combination, a body assembly including a first part suspensible by a wire line and a second part carried by the first part and movable axially of the first part, first and second dogs carried by one of said body assembly parts and movable laterally thereof between retracted and extended positions, said dogs being urged toward extended position, means carried by at least one of said body assembly parts and holding said second dog in retracted position while releasing the first dog for movement from retracted to extended position and operable responsive to relative axial movement between said body parts to move said first dog from extended to retracted position and to release said second dog for movement from retracted to extended position, detent means restraining said relative axial movement between the body parts and releasable upon predetermined force being applied to urge the body parts axially of each other, said first dog having a force transmitting connection with said second body part and when extended being engageable with said downwardly facing abutment upon upward movement of the tool to hold the second body part against upward movement therewith so that upon sufficient lifting force being applied to the first body part by the wire line, said detent means is released to permit said relative axial movement of the body parts to release said second dog and retract the first dog.

4. The tool of claim 3 wherein said first dog is freely movable downwardly past both said abutments when in extended position.

5. The tool of claim 3 wherein said second dog when extended is engageable with said upwardly facing abutment upon downward movement of the tool to resist downward movement of the tool therewith but is freely movable past both abutments upon upward movement of the tool.

6. The tool of claim 5 wherein said holding means is also operable to retract said first dog while releasing said second dog responsive to relative axial movement of the body parts in a direction opposite to that of the first mentioned relative axial movement.

7. A wire line tool adapted to be lowered into a well to selectively engage upwardly and downwardly facing abutments of an apparatus disposed in the well comprising, in combination, a body assembly having one part adapted to be supported by a wire line and another part carried by said one part and movable relative thereto, a first dog carried by the body assembly and moveable laterally of the body assembly from a retracted to an extended position and being engageable in extended position with said downwardly facing abutment when the tool is

moved upwardly in the well to resist such movement but movable freely past both said abutments when the tool is moving downwardly in the well, a second dog carried by the body assembly and moveable laterally of the body assembly from a retracted to an extended position and being engageable when in extended position with said upwardly facing abutment when the tool is moved downwardly in the well to resist such movement but movable freely past both said abutments when the tool is moved upwardly in the well, said dogs being urged toward extended position, means carried by the body assembly and holding said second dog retracted while the first dog is extended and movable to release said second dog upon said relative movement between the body parts, means carried by the body assembly and retracting said first dog responsive to said relative movement between the body parts, detent means connecting between said body parts resisting said movement and releasable upon application of a predetermined force tending to cause said relative movement between the body parts and a force transmitting connection between said first dog and said another body part so that upon engagement of said first dog with said downwardly facing abutment and the exertion of said predetermined force by said wire line on said one body part, said body parts are moved relative to each other to cause said first dog to be retracted and to permit the second dog to be extended.

8. A wire line tool adapted to be lowered into a well to selectively engage upwardly and downwardly facing abutments of an apparatus disposed in the well comprising, in combination, a body assembly having one part adapted to be supported by a wire line and another part carried by said one part and movable relative thereto, a first pair of dogs carried by the body assembly and moveable laterally of the body assembly from a retracted to an extended position and being engageable in extended position with said downwardly facing abutment when the tool is moved upwardly in the well to resist such movement but movable freely past both said abutments when the tool is moving downwardly in the well, a second pair of dogs carried by one of said body parts and moveable laterally of the body assembly from a retracted to an extended position and being engageable when in extended position with said upwardly facing abutment when the tool is moved downwardly in the well to resist such movement but movable freely past both said abutments when the tool is moved upwardly in the well, said dogs being urged toward extended position, means carried by the body assembly and holding said second dogs retracted while the first dogs are extended and movable to release said second dogs upon said relative movement between the body parts, means carried by the body assembly and retracting said first dogs responsive to said relative movement between the body parts, detent means connecting between said body parts resisting said relative movement between the body parts and releasable upon application of a predetermined force tending to cause said relative movement between the body parts, and a force transmitting connection between said first dogs and said another body part so that upon engagement of said first dogs with said downwardly facing abutment and the exertion of said predetermined force by said wire line on said one body part, said body parts are moved relative to each other to cause said first dogs to be retracted and to permit the second dogs to be extended.

9. A wire line tool manipulatable in a well to selectively engage upwardly and downwardly facing abutments of a well apparatus in the well comprising in combination, a body assembly adapted to be moved through the well by a wire line, a pair of oppositely facing dogs carried by the body assembly for movement laterally of the body assembly between extended and retracted positions and with one dog being engageable when extended with said upwardly facing abutment and with the other dog being engageable with the downwardly facing abut-

ment to resist movement of the tool therewith, said dogs being urged toward extended position, said body assembly including means alternately operable to retract one dog and release the other dog for movement to extended position responsive to force of predetermined magnitude being exerted on the body assembly to urge said one dog against the abutment engageable thereby and to retract said other dog and release said one dog responsive to force of predetermined magnitude being exerted on the body assembly to urge said other dog against the abutment engageable thereby.

10. In an apparatus including a ported conduit adapted to be positioned in a well bore, valve means shiftable in said conduit from a first to a second position to control flow through the port of said conduit, said conduit and valve means having portions providing a recess of predetermined length therebetween with the valve means shifted to its second position, and a tool for shifting said valve means to its second position and for indicating whether the valve means has been so shifted including a body manipulatable by a wire line, a first dog carried by the body and engageable with the valve means for shifting it to said second position upon movement of the tool in one direction in the conduit, said first dog being disengageable from the valve means, and a second dog carried by the body and biased laterally outwardly thereof to enter said recess and engage a wall thereof to thereby restrain movement of said body, said second dog being of a length to bridge across said conduit and valve means portions when the valve means is in other than its second position to thereby permit said body to move the second dog past the valve means to indicate the valve means is in a position other than a second position.

11. In an apparatus including a conduit adapted to be positioned in a well bore, a sleeve-like member in the conduit and shiftable axially from a first to a second position, said conduit and member having axially spaced portions movable apart upon movement of the member to its second position to provide a dog receiving recess therebetween; and a tool for shifting said member and for indicating when such shifting is complete including a body, a first dog carried by the body and urged outwardly of the body for movement to an extended position for engagement with said member to shift it to said second position upon movement of the body in one direction and disengageable from the member upon movement of the body in an opposite direction, a second dog carried by the body and spaced axially of the first dog in a direction to be situated laterally opposite said conduit and member portions upon movement of the body in said opposite direction, said second dog being biased laterally outwardly of the body and of a length to enter said recess only when the member has been shifted to its second position and when the member is in other than its second position to bridge across said conduit and member portions, said second dog when in said recess engaging said member to prevent movement of the body in said one direction thereby indicating the member is in its second position.

12. The apparatus of claim 11 in combination with a third dog carried by said body in extended position during lowering of the body through said conduit and engageable with a downwardly facing abutment in the well upon upward movement of the body, said first dog being engageable when extended with said member upon downward movement of the body to shift the member downwardly to its second position, and means carried by the body and holding the first dog in retracted position and operable upon engagement of the third dog with said abutment and a predetermined upward force being exerted on said body to release said first dog and retract the third dog.

13. The apparatus of claim 12 wherein said portion of said member is an upwardly facing abutment to prevent downward movement of the body when the second dog engages such abutment, means carried by the body for

holding the second dog retracted while the body is lowered into position in the well conduit and operable to release the second dog upon predetermined upward movement of the body.

14. In a well apparatus adapted to be lowered into a well conduit to engage a downwardly facing abutment carried by the well conduit and to apply an upward force to such abutment, a body, parts carried by the body and engageable with said abutment, a jarring mechanism having portions reciprocal relative to each other to provide a jarring action, one of said jarring mechanism portions being connected with said body so that upon reciprocation of the other portion, an upwardly directed jarring force is applied to the body, and a holding tool connected with said body including parts engageable with said conduit to restrain downward movement of the body while the first mentioned parts are in engagement with said abutment and thereby maintain the first mentioned parts in engagement with said abutment during actuation of said jarring mechanism.

15. An apparatus including a conduit adapted to be positioned in a well bore, a member positioned in said conduit to be shifted to control a well operation, a shifting tool comprising a body having first and second portions moveable relative to each other, a first part carried by the second body portion and movable laterally of the conduit to extended position to engage one of said member and conduit upon movement of said body in one direction within said conduit, a second part carried by the second body portion and movable laterally of the conduit to extended position to engage one of said member and conduit, said first and second parts being urged toward extended position, means carried by the first body portion and holding said second part in retracted position, said holding means being movable relative to the second body portion and to said second part to release the second part for lateral movement upon engagement of said first part with one of the conduit and member and application of force to the first body portion to move it relative to the second body position, and detent means carried by the body and resisting movement between said body portions and releasable upon a force of predetermined magnitude being applied to the first body portion.

16. A well apparatus including a ported conduit adapted to be positioned in a well bore, valve means shiftable to control flow of fluid through the conduit port, a tool for shifting the valve means including first and second dogs each movable from retracted to extended positions to respectively engage downwardly and upwardly facing portions of the valve means and thereby move it upwardly and downwardly respectively, said first and second dogs when in extended position respectively permitting the tool to move freely downwardly and freely upwardly through the conduit without engaging the valve means, said dogs being urged toward extended position, a first body part carrying the dogs and having a force transmitting connection with said first dog, a second body part adapted to be connected to a wire line and connected to the first body part for limited movement relative thereto upon the first dog engaging said downwardly facing portion of the valve means to restrain movement of said first body part while an upward force is being exerted by a wire line on the second body part, means carried by the second body part and holding the second dog in retracted position while the first dog is in extended position and movable with the second body part during said limited movement thereof to release the second dog and retract the first dog, and means connected between the body parts and restraining said limited movement of the second body part relative to the first body part until sufficient force has been applied by the wire line to shift the valve means and then, upon the application of a greater force by said wire line,

releasing second body part for said limited movement thereby retracting the first dog and releasing the second dog.

17. The apparatus of claim 16 in combination with means connected to the tool for supporting said tool independently of said wire line against downward movement through said conduit while the first dog is positioned to engage said valve means whereby the wire line support can be slackened off to jar the tool upwardly without said first dog being removed from its position for engagement with the valve means.

18. The apparatus of claim 17 wherein said supporting means comprises elements carried by one body part and resiliently biased to frictionally engage one of said conduit and valve means with sufficient force to support said tool against downward movement when otherwise unsupported by a wire line.

19. The apparatus of claim 17 wherein said supporting means comprises a body connected to said tool, a supporting dog carried by said body connected to said tool and normally held in retracted position while the tool is being lowered into the well bore, and means for releasing said supporting dog for movement to extended position to engage an upwardly facing portion of the valve means responsive to said first dog engaging its downwardly facing portion of the valve means and an upward force being exerted on said tool.

20. A well apparatus including a ported conduit adapted to be positioned in a well bore, valve means shiftable to control flow of fluid through the port of said conduit, a tool for shifting the valve means including first and second body parts, first and second dogs carried by the second body part and each being movable laterally of the second body part from retracted to extended positions to respectively engage downwardly and upwardly facing portions of the valve means and thereby move it upwardly and downwardly respectively, said first and second dogs when in extended position respectively permitting the tool to move freely downwardly and freely upwardly through the conduit without so engaging the valve means, said dogs being urged toward extended position, a first body part carrying the dogs and having a force transmitting connection with said first dog, a second body part adapted to be connected to a wire line and connected to the first body part for limited movement relative thereto, said body parts being connected together so the first body part is movable relative to the second body part upon one of said dogs engaging its portion of the valve means to restrain movement of said second body part while force is being exerted on the first body part, dog retractors connected to the first body part for movement thereby having means responsive to movement of the first body part in one direction relative to the second body part to engage and retract one dog while releasing the other dog for movement to extended position and, responsive to movement of the first body part in an opposite direction relative to the second body part, releasing said one dog for movement from retracted to extended position and engaging and retracting said other dog, and means restraining said relative movement between the body parts until a sufficient force has been applied to said first body part to shift the valve means and then upon the application of a greater force, releasing the body parts for said relative movement.
